DESIGN FOR A MOUTHPIECE FOR A TELEPHONE TRANSMITTER

David T. Eighmey, Jamaica, N. Y., assignor to Bell Telephone Laboratories, Incorporated, New York, N. Y., a corporation of New York

Application September 10, 1937, Serial No. 71,551

Term of patent 14 years

To all whom it may concern:

Be it known that I, David T. Eighmey, a citizen of the United States, residing at Jamaica, in the county of Queens and State of New York, have invented a new, original, and ornamental Design for a Mouthpiece for a Telephone Transmitter, of which the following is a specification, reference being had to the accompanying drawing, forming a part thereof.

Fig. 1 is a perspective view of a mouthpiece for a telephone transmitter, of my new design;

Fig. 2 is a front view of the mouthpiece;
Fig. 3 is a side view of the mouthpiece; and
Fig. 4 is a sectional view along the line 4—4 of Fig. 2.

I claim:
The ornamental design for a mouthpiece for a telephone transmitter as shown.

DAVID T. EIGHMEY.
